Primary Examiner — Ralf Seifert(74) *Attorney, Agent, or Firm* — Andrew Wilford(57) **CLAIM**

The ornamental design for a brassiere shoulder-strap closure, as shown and described.

DESCRIPTION

FIG. 1 is front perspective view from above of a half of the closure of this invention that is formed by two identical such halves;

FIG. 2 is a front elevational view of the closure half;

FIG. 3 is a side elevational view of the closure half, both side views being mirror-symmetrical identical;

FIG. 4 is a back elevational view of the closure half;

FIG. 5 is a bottom view of the closure half;

FIG. 6 is a front perspective view of the closure of this invention formed by two of the halves of FIGS. 1-5;

FIG. 7 is a front elevational view of the closure;

FIG. 8 is a side elevational view of the closure, both side views being mirror-symmetrical identical;

FIG. 9 is a back elevational view of the closure;

FIG. 10 is a bottom view of the closure;

FIGS. 11-20 are views corresponding to FIGS. 1-10 of a second embodiment of the closure;

FIGS. 21-30 are views corresponding to FIGS. 1-10 of a third embodiment of the closure; and,

FIGS. 31-40 are views corresponding to FIGS. 1-10 of a fourth embodiment of the closure.
